(57) **CLAIM**

The ornamental design for an equipment cabinet, as shown and described.

DESCRIPTION

FIG. 1 is a front perspective view of an equipment cabinet according to the invention;

FIG. 2 is a front elevation view of the equipment cabinet depicted in FIG. 1;

FIG. 3 is a side elevation view of the equipment cabinet depicted in FIG. 1;

FIG. 4 is a rear elevation view of the equipment cabinet depicted in FIG. 1;

FIG. 5 is top plan view of the equipment cabinet depicted in FIG. 1; and,

FIG. 6 is a bottom plan view of the equipment cabinet depicted in FIG. 1.

Although not depicted, the opposing side elevation view is a mirror image of the view of FIG. 3.
